APPARATUS FOR EXPANDING METAL CORNER BEADS.

Application filed June 14, 1924. Serial No. 720,099.

- This invention relates to machines for expanding slotted sheet metal blanks, particularly such as are bent into angle form for use as corner beads. 55
- 5 The invention is fully described in the following specification and shown in the accompanying drawings in which: 60
- Figure 1 is a side elevation of the front end of the machine;
- 10 Fig. 1^b is a similar view of the rear end of the same;
- Fig. 1^b shows a sectional view of the points of contact of the link and the bell crank;
- 15 Fig. 2 is a partial vertical section on the line 2 of Fig. 1;
- Fig. 3 is a partial horizontal section on the line 3 of Fig. 1 showing the main clutch and means for tripping;
- 20 Fig. 4 is an enlarged section on the line 4 of Fig. 3 showing the clutch disengaged;
- Fig. 5 is a plan view of the same showing the clutch in engagement at the beginning of the operating cycle;
- 25 Fig. 6 is a perspective view of the clutch detent;
- Fig. 7 is a perspective view of the bar for operating the detent;
- 30 Fig. 8 is an enlarged transverse view of the upper part of the machine on the line 8 of Fig. 1, showing the mechanism for operating the expander arms;
- Fig. 9 is a partial plan view on the line 9—9 of Fig. 8;
- 35 Fig. 10 is a longitudinal vertical section on the line 10 of Fig. 9;
- Fig. 11 is a vertical transverse section on the line 11 of Fig. 1 showing the cam for operating the bead gripping mechanism;
- 40 Fig. 12 is a horizontal section on the line 12 of Fig. 11;
- Fig. 13 is a vertical section on the line 13 of Fig. 1 showing the cam for operating the side gripping mechanism;
- 45 Fig. 14 is a horizontal section on the line 14 of Fig. 13;
- Fig. 15 is a vertical section on the line 15 of Fig. 1 similar to Fig. 13 but showing a cam for operating the side gripping device on the opposite side of the machine;
- 50 Figs. 16 and 17 are sections on the lines 16 and 17 respectively of Fig. 15;
- Fig. 18 is a transverse vertical section on the line 18 of Fig. 1 showing the mechanism feeding the slotted blank into the machine
- previously to expanding the same; 55
- Fig. 19 is an enlarged view of the clamping and expanding mechanism showing the center bead and side gripping mechanism in the gripping position previous to expanding but with no blank in the machine; 60
- Fig. 20 is an enlarged view of the same showing a blank held therein;
- Fig. 21 is a view similar to Fig. 20 showing the blank expanded previous to being released; 65
- Fig. 22 is a similar view showing the expander arms separated still more with the side grippers released;
- Fig. 23 is a similar view showing the expander arms in full open position, the bead gripper having fully opened, thereby dropping the expanded blank; 70
- Fig. 24 is a plan view of the rear end of the machine showing the trip mechanism which is operated by the incoming blank; 75
- Fig. 25 is a side elevation of the same;
- Fig. 26 is a front elevation of the cam for operating the expander arms;
- Fig. 27 is a plan view of the blank following the slitting operation; 80
- Fig. 28 is an end elevation of the completed blank;
- Fig. 29 is a side elevation of the same;
- Fig. 30 is an end elevation of the expanded corner bead; and 85
- Fig. 31 is a side elevation of the same.
- This machine is intended primarily for expanding slotted sheet metal corner beads of the type shown and described in my pending application Serial No. 676,733, filed November 24, 1923, and for carrying out the process of expanding described therein. 90
- This corner bead A as shown in Figs. 28 and 29 is made by slitting the blank on both sides of the center as shown in Fig. 27, thus forming two herring bone sections with a plain central portion which when the blank is bent along a longitudinal line forms the neck A' and the bead A². Marginal ribs A³ are likewise formed in the edges of the sheet. 95
- The embodiment illustrated comprises a machine having a series of vertical frames 32 which are all substantially alike and which are secured together by means of side members 33, 34, etc., the frames 33 resting upon a suitable base 35. 100
- Two expander shafts 36 and 37 extend throughout the length of the machine and

- are journalled in suitable bearings as shown in Fig. 8. A rocker arm 38 is keyed to the shaft 37 and has a link 39 pivotally connecting the outer end of the rocker arm with the outer end of the follower arm 40, the latter being pivotally mounted on a pin 41 carried by the frame 32. The follower arm 40 has a roller 42 journalled therein which rolls upon the face of the cam 43 which is 5 preferably adjustably mounted upon the cam shaft 44 as will later be described. This cam shaft is suitably journalled in the main frame.
- The opposite end of the rocker arm 38 (Fig. 8) is pivotally connected by means of a link 45 with a lever 46 on the shaft 36 so that the shafts 36 and 37 are simultaneously oscillated in opposite directions.
- Referring now to Fig. 18 a series of expander arms 47 and 48 are keyed to the shafts 36 and 37 respectively, and to these are bolted bars 49 and 50 which extend substantially throughout the length of the machine.
- Shafts 51 and 52 are journalled in the expander arms 47 and 48 respectively, these shafts likewise run substantially the length of the machine. The shaft 51 has keyed thereon a lever 53 which is pivotally connected to the link 54, the opposite end of the link being pivotally connected to the follower arm 55. This arm carries at its outer end a roller 56 which is held upon the face of the cam 57 by means of a spring 58. This cam is adjustably connected to the cam shaft 44.
- In Fig. 13 is shown a similar cam 59 on the shaft 44 which is similarly connected to the shaft 52.
- Referring now to Figs. 20 and 22, the shafts 51 and 52 carry cams 60 and 61 which are keyed thereto and which bear upon levers 62 and 63 which are pivotally mounted at 44 and 65 on the expander arms 47 and 48.
- Gripping jaws 66 and 67 are carried by the levers 62 and 63, which are the same length as the notched guides 68 and 69 forming a part of the longitudinal bars 49 and 50. Springs 66^a and 67^a normally hold these gripping jaws open. The longitudinal extending notches 70 and 71 therein are so placed that when the expander arms are in the closed position as shown in Figs. 18 and 20, the previously slotted blank A may be fed horizontally through the machine as will later be described along the top of the notched guides, the angular blank riding upon the upper edges of the rollers 72 which are journalled upon pins 73 in the longitudinal bars 49. A longitudinal shaft 75 is journalled at the top of the several frames 32 and carries a series of cams 76 which operate between levers 77 and 78 which are pivotally mounted at 79 on the frame members 32 and are held against the cam 76 by

a spring 80. Clamping jaws 81 and 82 are provided on the lower edges of these levers which are adapted to grip the neck portion A' of the blank A, a space 83 being provided between the clamping jaws 81 and 82 70 for the bead A² of the blank, so that the bead will be retained between the jaws 81 and 82 which extend substantially throughout the length of the expanding machine.

The shaft 75 is turned by means of a lever 75 84 which is pivotally connected at one end by a link 85, the opposite end of the link being connected to a follower arm 86 which is pivotally connected at 87 and has a roller 88 journalled to turn thereon. This roller 80 rolls upon the face of the cam 89 which is adjustably mounted upon the cam shaft 44.

From the foregoing it will be apparent that when a blank A of the type previously described is fed to the machine by mechanism, which will later be described, the gripping jaws 66, 67, 81 and 82 being open, the cam shaft 44 revolves and causes the cam 89 to lift the follower arm 86 against the action of the spring 86^a, thereby turning the shaft 75 and the cam 76, spreading the levers 77 and 78 and clamping the jaws 81 and 82 about the necked-in portion A' of the blank beneath the bead A². At the same time the cams 57 and 59 cause the shafts 51 and 52 to be turned to the position shown in Fig. 20, thereby similarly clamping the marginal ribs A³ of the blank between the gripping jaws 66 and 67 and the notches 70 and 71.

As the cam shaft 44 continues to revolve, the cam 43 raises the follower arm 40, thereby rocking the shafts 36 and 37 and swinging the expander arms 47 and 48 outwardly as shown in Fig. 21. This movement causes the blank to be expanded and to assume the form shown in Figs. 30 and 31.

When the parts have reached the position shown in Fig. 21, the high points of the cams 57 and 59 pass quickly from beneath the rollers thereby permitting the shafts 51 and 52 to move back to open position, thus raising the gripping jaws 66 and 67. During this time the expander arms 47 and 48 continue their outward movement as shown in Fig. 22. This movement is continued until a position of Fig. 23 is reached wherein the expander arms are separated sufficiently to permit the now expanded corner bead to drop between them as shown in Fig. 23. This is accomplished by the movement of the shaft 75 which is turned by the cam 59 as the latter turns, as shown in Fig. 11.

The mechanism for feeding the blank to the machine consists of a series of shafts 90 and 91, as shown in Figs. 1 and 1^a, all being driven continuously in the same direction by means of sprockets 92 and 93, the shaft 90 being driven by a chain 94 and sprocket 95, the latter being keyed on a shaft 96

which is journalled in suitable bearings and is driven by a sprocket 97 and chain 98 from a source of power not shown.

Referring now to Fig. 18, the shaft 91 is journalled within a sleeve 99 and carries a grooved sheave 100, the groove being adapted to rest upon the bead of the blank so that the friction created between the sheave and the blank will cause the latter to roll through the machine on the rollers 72. The sleeve 99 is pivotally mounted on trunnions 101 as shown in Fig. 18, so that the weight of the sleeve, shaft and sheave rests upon the bead of the blank.

As the blank nears the end of the gripping jaws, the bead encounters a trip finger 102 as shown in Fig. 18, which is mounted on a shaft 103 which is journalled in the main frame. A lever 104 is secured to the outer end of this shaft and this is pivotally connected to a link 105 (Fig. 1^a) which passes through a series of rollers 106 and has a stop 107 at its forward end, the stop being normally held against the bracket 108 by a spring 109. This link has a shouldered head 110 (Fig. 1^b) which is adapted to ride up over a ledge 111 against the action of the spring 112 as the link is drawn back by the spring 109. A bell-crank 113 carries the ledge 111 and is pivotally mounted at 114 on the forward frame 32. The other arm of the bell-crank 113 is normally drawn down by a spring 115 and is connected to a second bell-crank 116 by means of a link 117. The second bell-crank is fulcrumed at 118, the forward arm being connected by means of a link 119 to the lever 120 which is fulcrumed at 121 as shown in Figs. 1, 2 and 3. The outer end of the lever 120 is tapered as shown at 120^a (Fig. 7) and is adapted to slide into a tapered notch 122 in a detent 123. This detent is slidably mounted in a cylindrical member 124 keyed on the drive shaft 125 and normally pressed outward by means of a spring 126. A continuously driven gear 127 is journalled upon the drive shaft 125 and has a lug 128 adapted to being encountered by the detent when the latter is released.

It will be understood from the foregoing that when the blank is fed into the machine it will encounter the trip finger 102 near the far end of the machine, thus moving the trip finger, the lever 104 and the link 105 against the action of the spring 109. This link then acting through the bell-cranks 113 and 116, raises the outer end of the lever 120 thereby releasing the detent 123. The spring 126 then forces the detent into the path of the lug 128 thereby causing the gear 127 to turn the block 124. At the same time the link 105 in drawing forward the bell-crank 113 slips off the ledge 111 and the spring 115 immediately returns the tapered point of the lever 120 to its normal position

in the angular groove of the block 124 so that as the latter revolves the tapered point of the lever will encounter the tapered notch 122 of the detent 123 thereby forcing the latter to the position shown in Fig. 4 and disconnecting the driving block from the driving gear 127. Thus only one revolution of the cam shaft 44 is permitted upon a single actuation of the trip finger 102.

A belt 129 lies beneath the blank when in gripped position and passes around a pulley 130 on the shaft 96 and thence over a series of rollers 131 which support the upper strand of the belt, these rollers being journalled on the frame members 32 as shown in Figs. 1 and 1^a. This belt then passes down at the rear end of the machine over the pulley 132 and under the pulley 133 and thence back over a series of pulleys 134. When the expanded blank is dropped as shown in Fig. 23, it falls upon this belt and is carried out at the rear of the machine, where it is caught by an attendant.

During this time the cams have returned to the parts controlled thereby as shown in Fig. 18, wherein the expanding arms 47 and 48 are moved to their innermost position, but the gripping jaws are held open. The operator then inserts a new blank which rides over the rollers 72 and is propelled forward as previously described by means of the grooved sheaves 100. This blank continues to move forward until it encounters the trip finger 102, when the lever 120 is raised thereby releasing the detent 123 and causing the cam shaft 44 to make one complete revolution when it is again brought to rest as has been previously described.

During the time the blank is held by the gripping jaws the trip finger 102 is held in the retracted position wherein the forward end 110 of the link 105 is out of engagement with the bell-crank 113. As soon, however, as the expanded blank is released by the gripping jaws, the spring 109 returns the link 105 to its normal position as shown in Figs. 1 and 1^b, and on its return movement the end 110 is moved over the ledge 111 against the action of the spring 112.

Fig. 26 shows the expander cam 43 and on this is superimposed a diagram of operation of the other cams so as to illustrate the relation of the movements of the bead and side gripping jaws to the movements of the expander arms.

It is advisable to make provision for adjusting these movements somewhat and in Figs. 15, 16 and 17 I have shown the cam 57 bolted to a collar 57^a which is keyed to the cam shaft 44. The cam 57 has a lug 57^b which projects through an opening 57^c in the collar and screws 57^d in the collar permit of adjustment of the cam with respect to the cam shaft 44.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

I claim:

1. A machine for expanding slotted sheet metal blanks comprising a frame, two shafts journaled therein, means carried by said shafts for gripping the margins of said blanks, means for actuating said gripping means, and means for rotating said shafts to move said gripping means for expanding said blanks.
2. A machine for expanding slotted sheet metal blanks comprising a frame, two parallel shafts journaled therein, means carried by said shafts for gripping the margins of said blanks, means for actuating said gripping means, and means for rotating said shafts to move said gripping means for expanding said blanks.
3. A machine for expanding slotted sheet metal blanks comprising a frame, two parallel shafts journaled therein, lever arms carried by said shafts, means thereon for gripping the margins of said blanks, means for actuating said gripping means, and means for rotating said shafts to move said lever arms for expanding said blanks.
4. A machine for expanding corner bead blanks having a V-shaped cross-section and a central longitudinal bead, comprising means for gripping said central bead, means for gripping the margins of the corner bead, and means for increasing the distance between said gripping means for expanding said corner beads.
5. A machine for expanding corner bead blanks having a V-shaped cross-section and a central longitudinal bead, means for feeding a corner bead blank to the machine, comprising means for gripping said central bead, means for gripping the margins of the corner bead, and means for increasing the distance between said gripping means for expanding said corner beads, said last named means being operable by the corner bead blank when it has reached a predetermined position in the machine.
6. A machine for expanding corner bead blanks having a V-shaped cross-section and a central longitudinal bead, a frame, longitudinal shafts journaled in said frame, expander arms secured to said shafts, means carried by said arms for gripping the margins of said blanks, means for gripping the central bead, and means for rocking said shafts to move said expander arms away from each other.
7. A machine for expanding corner bead blanks having a V-shaped cross-section and a central longitudinal bead, a frame, longitudinal shafts journaled in said frame, expander arms secured to said shafts, means on said arms for guiding the corner bead blank as it is inserted endwise, means carried by said arms for gripping the margins of said blanks, means for gripping the central bead, and means for rocking said shafts to move said expander arms away from each other.
8. A machine for expanding corner bead blanks having a V-shaped cross-section and a central longitudinal bead, a frame, longitudinal shafts journaled in said frame, expander arms secured to said shafts, means for feeding the corner bead blank into the machine, means carried by said arms for gripping the margins of said blanks, means for gripping the central bead, and means for rocking said shafts to move said expander arms away from each other.
9. A machine for expanding corner bead blanks having a V-shaped cross-section and a central longitudinal bead, a frame, longitudinal shafts journaled in said frame, expander arms secured to said shafts, means carried by said arms for gripping the margins of said blanks, means for gripping the central bead, a cam shaft, and cams thereon for operating said shafts and means for expanding the blanks.
10. A machine for expanding corner bead blanks having a V-shaped cross-section and a central longitudinal bead, a frame, longitudinal shafts journaled in said frame, expander arms secured to said shafts, means carried by said arms for gripping the margins of said corner beads, a cam shaft, cams thereon for operating said shafts and gripping means, a bead gripping means including a shaft, and a cam on the cam shaft for operating said bead gripping shaft.
11. A machine for expanding corner bead blanks having a V-shaped cross-section and a central longitudinal bead, a frame, longitudinal shafts journaled in said frame, expander arms secured to said shafts, means carried by said arms for gripping the margins of said corner beads, a cam shaft, cams thereon for operating said shafts and gripping means, a bead gripping means including a shaft, a cam on the cam shaft for operating said bead gripping shaft, and means for controlling said cam shaft including a trip operable by said blank when it has reached a predetermined point in the machine.
12. A machine for expanding corner bead blanks of V-shaped cross-section and having central longitudinal beads, said machine comprising two parallel expander shafts, expander arms thereon, guides on said arms for the longitudinal insertion of said blanks,

means for gripping said central beads, means associated with said arms for gripping the margins of said beads, means for forcing said arms away from the gripped central beads, and means for releasing said margin gripping means after the expander arms have expanded the blank a predetermined amount while said expander arms continue to move apart, said central gripping means releasing to drop the expanded blank between the expander arms while they are separated. 13. A machine for expanding corner bead blanks of V-shaped cross-section and having central longitudinal beads, said machine comprising two parallel expander shafts, expander arms thereon, guides on said arms for the longitudinal insertion of said blanks, means for gripping said central beads, means associated with said arms for gripping the margins of said beads, means for forcing said arms away from the gripped central beads, means for releasing said margin gripping means after the expander arms have expanded the blank a predetermined amount while said expander arms continue to move apart, said central gripping means releasing to drop the expanded blank between the expander arms while they are separated.

veyor beneath the expander arms for carrying away the expanded blank. 30

14. A machine for expanding slotted sheet metal blanks comprising a frame, two shafts journaled therein, means carried by said shafts for gripping the margins of said blanks, means for actuating said gripping means, means for rotating said shafts to move said gripping means for expanding said blank, said gripping means releasing when the blanks are expanded, and said expanding means moving further apart after the blank is expanded to permit the expanded blank to drop therebetween. 40

15. A machine for expanding corner bead blanks having a V-shaped cross-section and central longitudinal beads, comprising means for gripping said central bead, means for gripping the margins of the corner beads, and means for increasing the distance between said gripping means for expanding said corner beads, said margin gripping means releasing when the blank is expanded while the gripping means continue to separate to permit the expanded blank to drop therebetween. 50 55

In witness whereof, I have hereunto set my hand this 13th day of May, 1924.

LEWIS E. CURTIS.
